CLAIM

The new, original and ornamental design for an airplane, thereof, as shown and described.

DESCRIPTION

FIG. 1 is a top view of an airplane according to a first embodiment of our invention.

FIG. 2 is a side view of the airplane thereof of FIG. 1, the opposite side view being a mirror image.

FIG. 3 is a bottom view of the airplane thereof of FIG. 1. FIG. 4 is a bottom perspective view of the airplane thereof of FIG. 1.

FIG. 5 is a top perspective view of the airplane thereof of FIG. 1.

FIG. 6 is a front view of the airplane thereof of FIG. 1.

FIG. 7 is a rear view of the airplane thereof of FIG. 1.

FIG. 8 is a top view of the airplane thereof of FIG. 1 according to a second embodiment of our invention.

FIG. 9 is a side view of the airplane thereof of FIG. 8, the opposite side view being a mirror image.

FIG. 10 is a bottom view of the airplane thereof of FIG. 8. FIG. 11 is a top perspective view of the airplane thereof of FIG. 8.

FIG. 12 is a bottom perspective view of the airplane thereof of FIG. 8.

FIG. 13 is a front view of the airplane thereof of FIG. 8; and, FIG. 14 is a rear view of the airplane thereof of FIG. 8.
